UNITED STATES PATENT OFFICE.

WILLIAM MARSHALL, OF DETROIT, MICHIGAN, ASSIGNOR TO BRIGGS MANUFACTURING COMPANY, OF DETROIT, MICHIGAN, A CORPORATION OF MICHIGAN.

HINGE FOR WINDSHIELDS.

Application filed September 2, 1924. Serial No. 735,459.

To all whom it may concern:

Be it known that I, WILLIAM MARSHALL, a citizen of the United States of America, residing at Detroit, in the county of Wayne 5 and State of Michigan, have invented certain new and useful Improvements in Hinges for Windshields, of which the following is a specification, reference being had thereto in the accompanying drawings.

10 This invention relates generally to hinge constructions and refers more particularly to those designed for connecting windshields, visors and the like to the supporting framework of vehicle bodies.

15 One of the essential objects of the invention is to simplify the mounting of windshields by providing a hinge that may be easily and quickly applied to the framework of the vehicle body and may be held in position thereon by means of only two screws.

20 Another object is to provide simple and effective means for preventing the hinge from rattling.

A further object is to provide a strong 25 and durable construction that can be manufactured at a comparatively low cost.

With the above and other objects in view, the invention consists of certain novel features of construction, combinations and 30 arrangements of parts as will be more fully described and particularly pointed out in the appended claims.

In the accompanying drawing;

35 Figure 1 is a front elevation of a portion of a vehicle body showing my invention applied thereto.

Figure 2 is an enlarged cross-sectional view.

40 Figure 3 is a fragmentary top plan view of the hinge embodying my invention.

Figure 4 is a cross sectional view of a slightly modified form of construction.

Referring now to the drawing in which like characters of reference designate corresponding parts throughout the several 45 views, the numeral 1 designates a windshield of conventional form that is preferably hinged at its upper edge to a suit-

able support such as the windshield header 2 at the front of a vehicle body of the closed type. This header is preferably constructed from sheet metal and is substantially U-shaped in cross section. The front and rear walls 3 and 4 respectively of the header are preferably secured to the top frame 5 of the vehicle body, while the bottom 6 of the header is preferably pressed upwardly at the outer edge thereof to form the longitudinally extending channel 7. As shown, the upper wall 8 of this channel preferably inclines upwardly from the lower edge of the front wall 4 and protects the hinge 9 from the weather. The hinge 9 preferably comprises the main supporting part 10 and the cooperating part 11. As shown, the main part 10 is preferably in the form of an elongated plate that is adapted to be attached to the inclined wall 8 of the channel 7 in the header and is provided at its forward edge with spaced longitudinally extending downwardly and rearwardly curved portions 12 which embrace a suitable pintle 13. The cooperating part 11 is also preferably in the form of an elongated plate that is readily secured by suitable means to the top rail 14 of the windshield frame and is provided at its forward edge with spaced longitudinally extending upwardly and rearwardly curved portions 15 that are swingingly mounted on the pintle 13 between the curved portions 12 of the main hinge part 10.

In order that the windshield 1 may be easily and quickly applied to the header, the main hinge part 10 is preferably provided at spaced points throughout its length with the forwardly extending struck-out spring tongues and the rearwardly extending lugs 17 which are engageable respectively with elongated openings 18 and 19 respectively in the upper wall 8 and back 20 of the channel 7 in the header.

In use, the lugs 17 are inserted through the elongated openings 19 in the back 20 of the channel 7 until the tongues 16 are

opposite to the elongated openings 18 in the inclined wall 8 of the channel. The windshield 1 is then raised so that the tongues 16 will be moved through the openings 18 and is subsequently moved forward so that the tongues 16 will engage the upper face of the inclined top 8 of the channel. As shown, the lugs 17 are of sufficient length to remain in the openings 19 when the windshield and hinge are moved forwardly, consequently when the tongues 16 engage the upper face of the inclined wall 8 of the channel 7, the windshield will be supported from the header by means of the lugs 17 and tongues 16. With this construction only two screws 21 are required to hold the hinge part 10 in fixed position against the inclined wall 8 of the channel 7 in the header. To facilitate assembly, these screws 21 are preferably inserted through suitable openings 22 at the opposite ends of the hinge part 10 and are adjusted in the inclined upper wall 8 of the channel 7 in the header.

In Figure 4 of the drawing, I have shown a slightly modified form of construction wherein the spaced front and rear walls 30 and 31 respectively of the header 32 are preferably secured to a wooden top frame 33 and are connected at their lower edges by a flat bottom 34. With this construction the lugs 35 of the main hinge part 36 preferably extend through spaced elongated openings 37 in a depending flange 38 at the rear edge of the bottom 34 while the tongues 39 are inserted through spaced elongated openings 40 in the bottom 34.

From the foregoing description it will be readily apparent that the windshield may be easily and quickly attached to or detached from the windshield header of the vehicle body. Inasmuch as only two screws are required to hold the main hinge part in position, it is also apparent that the job of assembly may be readily performed by only two workmen upon opposite sides of the vehicle body as it moves along on a track, thus saving considerable time, labor and expense. Moreover, the spring tongues struck-out from the main hinge part cooperate with the bottom of the header to effectively prevent the hinge from rattling.

While it is believed that from the foregoing description, the nature and advantages of the invention will be readily apparent, I desire to have it understood that I do not limit myself to what is herein shown and described and that such changes may be resorted to when desired as fall within the scope of what is claimed.

What I claim as my invention is:

1. The combination with a windshield, and a hinge secured thereto, of a metallic windshield header extending over said windshield having openings therein, means

for supporting said windshield from said header including tongues struck-out from said hinge engaging certain of said openings, and lugs projecting from said hinge engaging other of said openings. 70

2. The combination with a windshield, and a hinge secured thereto, of a metallic windshield header extending over said windshield having openings therein, means for supporting said windshield from said header including tongues projecting from said hinge engaging certain of said openings, and lugs projecting from said hinge engaging other of said openings, and means for securing said windshield to said header including headed elements at the ends of said hinge engaging said header. 75

3. The combination with a windshield, of a hinge secured thereto, a windshield header having a longitudinally extending channel receiving said hinge, and means for supporting said windshield from said header including tongues projecting from said hinge engaging one wall of said channel, and lugs projecting from said hinge engaging another wall of said channel. 80

4. The combination with a windshield, of a hinge secured thereto, a windshield header having a longitudinally extending channel receiving said hinge, means for supporting said windshield from said header including substantially L-shaped tongues struck-out from said hinge and engaging one wall of said channel, and lugs projecting rearwardly from said hinge and engaging another wall of said channel, and means for securing said hinge to said header including headed elements at the ends of said hinge engaging said header. 95

5. The combination with a windshield, of a hinge secured thereto, a sheet metal header having an inverted substantially L-shaped channel at the bottom thereof, the sides of said channel having spaced openings therein, tongues struck-out from said hinge engaging the openings in one side of said channel, and lugs projecting from said hinge engaging the openings engaging another side of said channel. 105

6. The combination with a windshield, of a hinge secured thereto, a support for the windshield having a longitudinally extending channel receiving the hinge, said channel having openings in two sides thereof, and projections on the hinge engaging said openings. 110

7. The combination with a windshield, of a support therefor having a longitudinally extending channel therein, the back and upper wall of said channel having openings therein, and a hinge secured to said windshield having struck-out tongues engaging the openings in the upper wall of said channel, and lugs engaging the back of said channel. 125

8. The combination with a windshield, of a supporting header therefor having an upwardly and rearwardly inclined face and a depending face at the rear of the inclined face, means for supporting the windshield including a hinge having a part provided with upwardly offset tongues projecting through the inclined face aforesaid and rearwardly

extending lugs projecting through the depending face, and securing means for the windshield including a headed element engaging said hinge part and one of the faces aforesaid.

In testimony whereof I affix my signature.

WILLIAM MARSHALL.
